UNITED STATES PATENT OFFICE

CHARLES H. THAYER, OF MOUNT PLEASANT, NORTH CAROLINA

SAW FILER FOR COTTON GINS

Application filed March 10, 1930. Serial No. 434,768.

This invention relates to a device for filing the saws of cotton gins and delinter machines, the general object of the invention being to provide a device which will file two or more saws at one time, depending on the number of heads installed in the machine, with means for adjusting the parts to operate on saws of different diameters.

Another object of the invention is to provide means for rotating the saws step by step so that the files can come in contact with each tooth of a saw.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a top plan view showing the device in use.

Figure 2 is an elevation of Figure 1.

Figure 3 is a view of the side opposite to that shown in Figure 2.

Figure 4 is a bottom plan view.

Figure 5 is a section on line 5—5 of Figure 2.

Figure 6 is an enlarged bottom plan view showing the means for adjusting the clamping mechanism which engages the spacer blocks of the saw roller.

Figure 7 is a section on line 7—7 of Figure 6.

Figure 8 is a section on line 8—8 of Figure 3.

Figure 9 is a plan view showing the means for moving the files toward and away from each other.

Figure 10 is a section on line 10—10 of Figure 9.

Figure 11 is a view of the support for the rear end of the machine.

Figure 12 is a fragmentary elevation of one of the forked bars.

In these drawings, the numeral 1 indicates the base of the machine, the rear end of which

is supported by the leg 2, this leg consisting of the two straps 2' which are connected to opposite sides of the base by the pins 3 and which are connected at their lower ends to the post 4 by the nuts 5, a curved member 6 being pivoted at its center to the lower end of the post and rods 7 are pivotally connected with the ends of the member 6 and are adjustably connected with the upper end of the post by the clamp 8. By adjusting the rods 7 in the clamp, the member 6 can be positioned to cause the leg to hold the base level on irregular surfaces.

An arm A is adjustably connected with the bottom of the opposite end of the base, this arm being composed of the two parts 9 which have their inner ends bent to form the yoke-shaped part 10, the limbs of which are slidably supported on the under face of the base by the brackets 11.

A lever 12, pivoted at 13 to the under face of the base, has a pin and slot connection, shown generally at 14, with an ear 15 on one of the parts 9 so that by shifting this lever, the arm can be moved forwardly or rearwardly, as desired. A clamp 16 engages portions of the parts 9 and a screw bolt 17 passes through the base and through said clamp so that by tightening this screw bolt, the clamp can be caused to grip the arm and thus hold it in adjusted position. The arm curves upwardly beyond the end of the base and has an upright part A' at its outer extremity. At the upper end of this upright part, the two parts 9 are fastened together and these parts 9 form a space for receiving a saw. One of the parts 9 is provided with a curved depending part 9' which carries an adjustable shoe 18 at its lower end for engaging one of the spacers 19 of the saw assembly.

A yoke 20 is slidably arranged on the upright part A' through means of the bolt 21 which passes through the upright part and through slots 22 in the limbs of the yoke and this yoke can be adjusted vertically by means of the set screw 23 passing through a threaded hole in the bight of the yoke, with its lower end rotatably connected with the upper end of the upright. The lower ends of the limbs of the yoke are offset and a shoe 24 is pivoted

to the extremity of each limb, one of these shoes engaging the spacer 19 and the other the spacer on the other side of the saw which passes through the space between the parts 9. Each shoe is limited in its pivotal movement by the pin and slot arrangement shown generally at 25. Thus the shoes 18 and 24 can be adjusted to engage spacers 19 of various sizes. A spring arm 26 is arranged to engage the spacer 19 at a point opposite the point of engagement of the spacer by the shoe 18, and this spring is fastened to an upright arm 27 pivoted at its lower end to the lower part of a lever 28 which is pivoted at its lower end to the lower end of the offset part 15 of a limb of a yoke, this lever 28 having a curved upper end formed with a slot 29 through which passes a bolt 30 carried by said limb of the yoke so that by tightening 20 the wing nut 31 on said bolt, the lever 28 can be held in adjusted position. An arm 32 is pivoted at its lower end to the lever 28 and has a slot 33 in its upper end which receives a pin 34 in a small lever 35 which is pivoted to the lever 28. Thus by adjusting 25 the lever 28, the spring arm 26 can be moved against the spacer 19, after which the lever 28 is clamped in position by tightening the wing nut 31. Then by swinging downwardly the small lever 35, the arm 32 is moved outwardly against the arm 27 so as to move 30 said arm 27 and the spring arm 26 to cause the arm to exert pressure on the spacer and thus clamp the main arm A to the saw assembly. This will fasten the front end of 35 the device to the saw assembly and as will be seen, the parts are adjustable so that they can be clamped on spacers of different sizes. By adjusting the arm A by the lever 12, the position of the base and the parts thereon can 40 be adjusted to suit saws of different sizes.

A shaft 36 is rotatably mounted on the top of the base by means of the bearing members 37 and this shaft can be turned either by hand 45 by attaching a crank handle to one end of the shaft or it can be turned by a motor M suitably supported by the base and having its shaft geared to the shaft 36 through the gearing shown generally at 38. A shaft 39, having a crank 40 at each end thereof, is rotatably arranged on the base and is connected with the shaft 36 by the gears 41 so that the crank shaft is driven from the shaft 36. The cranks extend in opposite directions and a 55 connecting rod 42 is connected with each crank.

Two sets of front and rear uprights 43 are supported by the base and each upright of each set has adjustably connected therewith 60 the upper guides 44. The guides of each set are connected together by a bar 45 which is adjustably connected with the front and rear uprights by the bolts 45' passing through the slots 43'. Each upright carries a pair of 65 lower guides 46, the upper one of each pair

being adjustable by the bolt and slot connections 47 which connect said guide with the upright. A bar 48 passes between the upper guides of each set, said bar passing under the bar 45 and a bar 49 passes through the lower 70 guides of each set. The lower guides are arranged to hold the bar 49 in a horizontal position, while the upper guides support the bar 48 in a diagonal position and the lower bar has an upright rear end which is formed 75 with a slot 50 to receive a bolt 51 which passes through the rear end of the bar 48 so that the rear end of the bar 48 is pivotally and slidably connected with the upstanding rear end of the bar 49. Each upstanding part of the 80 bar 49 is pivotally connected to a connecting rod 42 so that the rotation of the crank shaft 39 will reciprocate the bars 48 and 49.

An outwardly extending arm 52 is connected with each of the upper bars 48 and an inwardly extending arm 53 is connected with each of the lower bars 49. An upright member 54 is rotatably connected with each arm and has a hole therein to receive the file carrying rod 55 which is held in adjusted position by the set screw 56. Each file carrying rod is formed with a channel shaped forward end 57 to engage part of a file 58 and an adjustable clamp 59 is carried by each rod 55 to clamp the rear part of the file. Thus the 95 file is adjustably connected with its carrier rod and the rod can be adjusted longitudinally in the rotatable member 54.

A short bar 60 is connected in spaced relation to each reciprocating bar and a forked bar 61 of spring material is movably connected with each short bar by having a notch in its rear end engaging a projection 62 on a slotted member 63 which is adjustably fastened to the short bar by a screw 64, with a 100 leaf spring 65 held in place by the screw and pressing against the rear end of a forked bar 61. A bolt 66 is carried by each short bar and passes through a hole in the forked bar and this bolt carries a spring 67 which bears 105 against the forked bar and against a nut 68 on the bolt, this spring permitting yielding movement of the forked bar toward and away from the short bar. The forward end of the forked bar is bent at right angles with 110 its extremity forked and the forward end of the file carrying rod passes between the prongs of this forked part. The spring 67 and the spring nature of the bar 61 causes the forked bar to exert pressure on the file carrying rod. The springs 67 can be adjusted 115 by the nuts 68 to give the files a uniform tension and the adjustment at the rear end of each forked rod, consisting of the member 63 and the spring 65, enables the parts to be adjusted to overcome wear and also enables the file to be set parallel with the saw tooth.

A pair of bars 69 is transversely arranged at the front end of the base, the bars being 120 slidably arranged on the base and each bar 125

carries a pair of uprights 70, an upright on each bar engaging a file carrying rod of each set and these uprights are so formed that they tend to hold the file carrying rods in the 5 forked ends of the forked bars 61. A stop 71 on one edge of the base limits movement in one direction of one of the bars 69 and a lever 72 is pivoted to a right angle extension at the opposite end of the other bar, said 10 lever engaging an upright 70 on the first bar when the lever is swung outwardly so as to move the bars in opposite directions and thus cause the uprights 70 to move the file carrying rods of each set in opposite directions 15 so as to move the files of each set away from each other. This will free the files from the saw. When the lever 72 is swung inwardly, the uprights 70 will move away from the file carrying rods of each set so that the spring 20 actuated forked members 61 will press the file carrying rods away from each other and thus cause the files to be pressed against the saw, and these spring actuated forked members impart movement to the upright carrying 25 bars 69 when the lever is swung inwardly. As will be seen from Figure 1, the arms 52, the forked members 61 and the uprights 70 hold the file carrying rods of each set in a forwardly convergent position with the files 30 crossing each other diagonally with the saw between them. When the files are engaging a saw, the carriers do not engage the uprights as the saw prevents them from doing so. The spring actuated members 61 press 35 the files against the saw.

As before stated, by swinging the lever 72 outwardly, the files will be opened or moved away from each other so that they will disengage the saw and thus permit the 40 saw to be moved to the next tooth. The parts are so arranged that the files will file a tooth square in front and round at the back, which is considered the proper way to sharpen a tooth of a gin saw.

45 A member 74 is arranged under the base and has an upwardly curved front part 74' which is connected with the forward part of the arm A by a slot and pin connection shown generally at 75, so that the member 50 74 is movably supported by the arm A at its forward end. A stationary jaw 76 is adjustably connected to the member 74 by the bolts 77 passing through the stationary jaw and through the slot 78 in the member 74. A movable jaw 79 is pivoted between the 55 ears 80 carried by the stationary jaw. The front end of the movable jaw carries a pointed screw 81 for gripping a saw blade between itself and the stationary jaw. A roller 82 is carried by the shank of each of the jaw members and a lever 83, pivoted at its rear end to a bracket 84, fastened to the under face of the base, has its front end 60 adapted to pass between the two rollers so

as to move the movable jaw into clamping position.

A pair of links 85 connects the front part of the lever 83 to the front end of a lever 86 rotatably supported intermediate its ends 70 on a shaft 87 rotatably supported on the under side of the base and the rear end of said lever 86 carries a pin 88 for engaging a cam 89 in the gear 41 which is carried by the shaft 36. Thus on each revolution of 75 the gear 41 on the shaft 36, the lever 86 is rocked to move the lever 83 to cause the front end of said lever 83 to pass between the rollers 82 of the jaw members to cause the movable jaw to clamp the blade of the saw 80 passing through the slot in the arm A and as soon as the pin leaves the low part of the cam, the lever 83 is moved out of engagement with the rollers so that the jaws release the saw. 85

A second lever 90 is fastened to the shaft 87 intermediate its ends and has a pin 91 at its rear end for engaging the cam 89 and the front end of said lever has a slot 92 therein in which slides a block 93 to which the 90 upper ends of a pair of links 94 are connected. An extension of the member 74 passes between the straps and bolts 95 pass through the straps above and below the extension, so that said extension is caused to move with the 95 links when the same are moved vertically by the rocking movement of the lever 90 under the action of the cam 89. This action will cause the member 74 to swing on its pivot 75 and the upward movement of the member 74 100 takes place when the jaws are in gripping position so that the saw assembly will be rotated by this upward movement of the member 74 so as to bring another tooth of each of the saws being operated on by the files into 105 position to be engaged by said files. The extent of movement of the member 74 by the lever 90 is adjusted through means of a bar 96 which is connected with the block 93 at its front end and has its rear end adjustably 110 connected to a bracket 97 secured to the under side of the base and having a pin 98 thereon for engaging any one of a plurality of holes 99 in the rear end of the bar 96. A spring 100 holds the parts in adjusted position. 115

The motor is supported by the depending parts 101 from the base and the saw assembly is rotatably supported by the legs 102 having the rollers 103 at their upper ends for 120 engaging the shaft of the saw assembly.

After the parts are set up, as shown in Figures 1, 2 and 3, and the front of the device connected with the spacers of the saw assembly, with one of the saws passing through the slot in the arm A, the parts are adjusted to cause one set of files to engage the second saw from the saw which passes through the slot in the arm and the other set of files engages the second saw on the opposite side of 130

the saw which passes through the slot. The shaft 36 is then rotated either by the hand or by the motor so that the bars 48 and 49 will be reciprocated to cause the files to file 5 the teeth of the two saws. Each set of files makes two forward movements and two rearward movements on each revolution of the shaft and then the saws are moved one step by the means operated by the cams so as to bring another tooth of the saw in position to be acted on by the files. The operation continues until all the teeth on the two saws are filed, after which the lever 72 is swung outwardly to open the files and then the parts are 10 adjusted on another saw so that the two sets of files can file two other saws.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A saw filing device of the class described comprising a reciprocating member composed of a horizontal lower part and a diagonally arranged upper part, guideways 30 for said parts, means for slidably connecting the raised rear end of the inclined part with the rear end of the other part, a lateral arm extending in one direction from the lower part, a lateral arm extending in an 35 opposite direction from the upper part, a file carrier rotatably connected to each arm whereby the carriers have swinging movement toward and away from each other, a file connected to the forward end of each carrier, said files crossing each other diagonally 40 with the saw between them, and spring means for pressing the carriers away from each other to press the files against the saw.

2. A saw filing device of the class described comprising a reciprocating member composed of a horizontal lower part and a diagonally arranged upper part, guideways 45 for said parts, means for slidably connecting the raised rear end of the inclined part with the rear end of the other part, a lateral arm extending in one direction from the lower part, a lateral arm extending in an opposite direction from the upper part, a file carrier rotatably connected to each arm 50 whereby the carriers have swinging movement toward and away from each other, a file connected to the forward end of each carrier, spring means for pressing the carriers away from each other, stop means 55 against which the spring means hold the carriers when the saw is not between the files and manually actuated means for moving the stop means apart whereby the spring means will separate the files and thus move 60 them away from the saw.

3. A saw filing device of the class described comprising a reciprocating member composed of upper and lower parts, the lower part being horizontally arranged and the upper part sloping downwardly and forwardly, means for slidably connecting together the rear ends of said parts, a pair of file carriers connected to opposite sides of the member and supported for swinging movement toward and from each other, a file connected to the forward end of each carrier, said carriers converging forwardly with the files crossing each other diagonally and engaging opposite sides of the saw tooth, means for yieldingly pressing the carriers 75 away from each other to cause the files to be pressed against the tooth, a drive shaft, means for reciprocating the member therefrom, means for moving the saw intermittently to cause the files to engage different teeth of the saw and means for actuating the saw moving means from said shaft.

4. A saw filing device of the class described comprising a reciprocating member composed of upper and lower parts, the lower part being horizontally arranged and the upper part sloping downwardly and forwardly, means for slidably connecting together the rear ends of said parts, a pair of 80 forwardly converging file carriers connected to opposite sides of the member and supported for swinging movement toward and from each other, a file connected to the forward end of each carrier, the files crossing 85 each other diagonally and engaging opposite sides of the saw tooth, means for yieldingly pressing the carriers away from each other to cause the files to be pressed against the tooth, a drive shaft, means for reciprocating the member therefrom, means for moving the saw intermittently to cause the files to engage different teeth of the saw, means for actuating the saw moving means from said shaft, 90 means for adjusting the tension of the yieldable means and means for 95 adjusting the saw moving means to move the saw any desired distance.

5. A device for filing saws of cotton gins and the like, comprising a base, an arm adjustably connected with the lower part of the base and having a curved forward end slotted to receive one of the saws of the assembly, adjustable clamping means carried by the arm for engaging spacers of the assembly, a pair of reciprocating members on the base, a pair of forwardly converging file carriers connected to opposite sides of each member and supported for swinging movement toward and from each other, a file connected to the forward end of each carrier, the files of each pair of carriers crossing each other diagonally and engaging opposite sides of a saw tooth, means for yieldingly pressing the carriers of each pair away from each other to cause the files to be pressed against the 100

- tooth, the files of one set engaging a saw on one side of the arm and the files of the other set engaging the saw on the opposite side of the arm, means for moving the saw assembly intermittently to bring other teeth into position to be engaged by the files and means for actuating the reciprocating members. 5

6. A device for filing saws of cotton gins and the like, comprising a base, an arm adjustably connected with the lower part of the base and having a curved forward end slotted to receive one of the saws of the assembly, adjustable clamping means carried by the arm 10 for engaging spacers of the assembly, a pair of reciprocating members on the base, a pair of forwardly converging file carriers connected to opposite sides of each member and supported for swinging movement toward and 15 from each other, a file connected to the forward end of each carrier, the files of each pair of carriers crossing each other diagonally and engaging opposite sides of a saw tooth, means for yieldingly pressing the carriers of each pair away from each other to cause the files to be pressed against the tooth, the files of one set engaging a saw on one side of the arm and the files of the other set engaging a saw on the opposite side 20 of the arm, means for moving the saw assembly intermittently to bring other teeth into position to be engaged by the files, a drive shaft supported by the base, a crank shaft driven therefrom, connecting rods connecting the cranks of the shaft with the reciprocating members and means for operating the saw feeding means from the drive 25 shaft. 30

7. A device for filing saws of cotton gins and the like, comprising a base, an arm adjustably connected with the lower part of the base and having a curved forward end slotted to receive one of the saws of the assembly, adjustable clamping means carried by the arm 35 for engaging spacers of the assembly, a pair of forwardly converging file carriers connected to opposite sides of each member and supported for swinging movement toward and from each other, a file connected to the forward end of each carrier, the files of each pair of carriers crossing each other diagonally and engaging opposite sides of a saw tooth, means for yieldingly pressing the carriers of each pair away from each other to cause the files to be pressed against the tooth, the files of one set engaging a saw on one side of the arm and the files of the other set engaging a saw on the opposite side 40 of the arm, means for moving the saw assembly intermittently to bring other teeth into position to be engaged by the files, a drive shaft supported by the base, a crank shaft driven therefrom, connecting rods connecting the cranks of the shaft with the reciprocating members, means for operating the saw feeding means from the drive shaft, such means consisting of cam means on the drive shaft, a pair of levers operated by the cam means, saw clamping means operated by one of the levers, means for moving the clamping means when the same are in clamping position by the other lever and means for adjusting the saw moving means whereby the saw can be moved certain desired distances. 45

8. A device for filing saws of cotton gins and the like, comprising a base, an arm adjustably connected with the lower part of the base and having a curved forward end slotted to receive one of the saws of the assembly, adjustable clamping means carried by the arm 50 for engaging spacers of the assembly, a pair of forwardly converging file carriers connected to opposite sides of each member and supported for swinging movement toward and from each other, a file connected to the forward end of each carrier, the files of each pair of carriers crossing each other diagonally and engaging opposite sides of a saw tooth, means for yieldingly pressing the carriers of each pair away from each other to cause the files to be pressed against the tooth, the files of one set engaging a saw on one side of the arm and the files of the other set engaging a saw on the opposite side 55 of the arm, means for moving the saw assembly intermittently to bring other teeth into position to be engaged by the files, a drive shaft supported by the base, a crank shaft driven therefrom, connecting rods connecting the cranks of the shaft with the reciprocating members, means for operating the saw feeding means from the drive shaft, such means consisting of cam means on the drive shaft, a pair of levers operated by the cam means, saw clamping means operated by one of the levers, means for moving the clamping means when the same are in clamping position by the other lever and means for adjusting the saw moving means whereby the saw can be moved certain desired distances. 60

9. A saw filing device of the class described comprising a base, a clamping arm slidably connected with the base, a lever for shifting the arm, means for holding the arm in adjusted position, adjustable clamping parts carried by the arm, a second arm pivotally connected at its forward end to the first arm, stationary and movable clamping members carried by the second arm for clamping a saw, a lever for moving the movable clamping member to open and closed position, a cam operated lever for moving the first lever, a second cam operated lever for moving the second arm to cause the clamping means to move the saw and cam means for actuating the cam operated levers and saw filing means carried by the base. 65

10. A saw filing device of the class described comprising a base, a clamping arm slidably connected with the base, a lever for shifting the arm, means for holding the arm 70
